(57) **CLAIM**

The ornamental design for falling snowflake string lights, as shown and described.

DESCRIPTION

FIG. 1 is a perspective view of the falling snowflake string lights.

FIG. 2 is a front view of the falling snowflake string lights.

FIG. 3 is a back view of the falling snowflake string lights.

FIG. 4 is a side view of the falling snowflake string lights.

FIG. 5 is an opposite side view of the falling snowflake string lights.

FIG. 6 is a top view of the falling snowflake string lights; and, FIG. 7 is a bottom view of the falling snowflake string lights. The broken lines illustrate environmental matter, and form no part of the claimed design.
